CLAIM

The ornamental design for an artificial garland with micro LED, as shown and described.

DESCRIPTION

FIG. 1 is a front perspective view of an artificial garland with micro LED, showing my new design;

FIG. 2 is a rear perspective view thereof;

FIG. 3 is a front elevation view thereof;

FIG. 4 is a rear elevation view thereof;

FIG. 5 is a left side elevation view thereof;

FIG. 6 is a right side elevation view thereof;

FIG. 7 is a top plan view thereof;

FIG. 8 is a bottom plan view thereof;

FIG. 9 is an enlarged view of a portion labeled, 'FIG. 9' in FIG. 1;

FIG. 10 is an enlarged view of a portion labeled, 'FIG. 10' in FIG. 5;

FIG. 11 is an enlarged view of a portion labeled, 'FIG. 11' in FIG. 5;

FIG. 12 is an enlarged view of a portion labeled, 'FIG. 12' in FIG. 6;

FIG. 13 is an enlarged view of a portion labeled, 'FIG. 13' in FIG. 6;

FIG. 14 is an enlarged view of a portion labeled, 'FIG. 14' in FIG. 7;

FIG. 15 is an enlarged view of a portion labeled, 'FIG. 15' in FIG. 8; and,

FIG. 16 is another perspective view of the artificial garland with micro LED, shown in an used condition with leaves in broken lines.

The dash dot dash lines in FIGS. 1 and 5-15 are for the purpose of depicting the cut line of the enlarged view and form no part of the claim. The even broken lines in FIG. 16 showing of a leaves depict environmental structure that form no part of the claimed design.
